(57) **CLAIM**

The ornamental design for a set of earphones, as shown and described.

DESCRIPTION

FIG. 1 is a front perspective view of a set of earphones;
FIG. 2 is a front elevation view of the set of earphones;
FIG. 3 is a rear elevation view of the set of earphones;
FIG. 4 is a left side elevation view of the set of earphones;
FIG. 5 is a right side elevation view of the set of earphones;
FIG. 6 is a top plan view of the set of earphones; and,
FIG. 7 is a bottom plan view of the set of earphones.
The broken lines shown in the cord of the set of earphones
illustrate indeterminate length of the cord.
